COMBINED TELEPHONE BENCH AND LAMP

Alfonso G. M. Giardino, Anaheim, Calif.

Application April 23, 1956, Serial No. 41,164

Term of patent 14 years

(Cl. D33—14)

Figure 1 is a perspective view of the combined telephone bench and lamp, embodying my new design;

The dominant features of the design reside in the portions shown in full lines.

I claim:

The ornamental design for a combined telephone bench and lamp, substantially as shown and described.
